CLEANING IMPLEMENT FOR FIREARMS

Carl W. Gilligan, East Longmeadow, Mass.

Application January 23, 1942, Serial No. 427,930

2 Claims. (Cl. 15—143)

(Granted under the act of March 3, 1883, as amended April 30, 1928; 370 O. G. 757)

The invention described herein may be manufactured and used by or for the Government for governmental purposes, without the payment to me of any royalty thereon.

This invention pertains to a flexible shaft cleaning tool for the barrel chamber of a rifle.

Because of space limitations at the breech portion of a modern gun of the Garand type, considerable difficulty has been experienced in properly cleaning the barrel chamber. When the bolt is retracted to provide access to the chamber, the follower is presented in an elevated position. This hinders the insertion of a cleaning rod in the barrel chamber and prevents a conventional rod from being accurately aligned with the axis of the bore. Since it is customary to oscillate or rotate the cleaning rod as well as to reciprocate it axially in the chamber, the proper bushing or swabbing action so as to provide a uniformly clean bore has not been possible. Furthermore, with cleaning tools which heretofore have been employed, interference with the follower and various surfaces on the receiver of the gun have resulted when the tool was manipulated. This seriously impaired the effectiveness of the device and the speed of operation. Resort was made to curved or pivotally jointed rods to avoid some of these difficulties. However these difficulties were but partially corrected and the cleaning operation was still slow and somewhat clumsy.

It is therefore an object of this invention to provide a cleaning device which is arranged for quick insertion and removal, swift and facile manipulation, and accurate alignment with the axis of the barrel chamber of a gun.

Another object of the invention is to provide a rotary cleaning tool for the barrel chamber of a rifle which is free from operational interference by elements at the breech end of the rifle.

A further object of the invention is to provide a cleaning implement for use in the cramped quarters at the breech portion of a gun.

An additional object of the invention is to provide a cleaning device which is adapted for continuous rotation as well as reciprocation in the gun breech when the handle of the device is at an angle to the axis of the cleaning member of the device.

The principal object of this invention is to provide an extremely flexible cleaning tool for the breech end of a rifle that is capable of transmitting a high torque at any angle of flexing.

The specific nature of the invention as well as other objects and advantages thereof will

clearly appear from a description of a preferred embodiment as shown in the accompanying drawing in which:

Fig. 1 is a view in side elevation of the assembled implement.

Fig. 2 is an exploded elevational view of the device, with a part thereof in section.

Fig. 3 is an enlarged sectional detail of a portion of the tool.

Fig. 4 is a top plan view of the breech portion of a Garand rifle showing the tool in its operative position, and

Fig. 5 is a view in side elevation of a swab tip adapted for use in the tool chuck.

Referring to the drawing, the implement comprises a handle portion 10 affixed to a shank 11 to which is attached a helical spring 12. Secured to the other extremity of the spring is a notched chuck element 13 provided with a movable internally threaded collar 14. A detachable chuck engaging element 15 having threads 16 is arranged for threaded engagement with the internally threaded collar 14 and positive coupling with chuck element 13. Element 15 is provided with a hollow internally threaded extremity 17 which is conditioned to receive a threaded fitting 18 in a cleaning attachment 19 as shown in Figs. 1 and 2. This member is provided with an elongated, substantially cylindrical brush 20 having a diameter somewhat in excess of that of the barrel chamber. A pair of helically twisted wire rods 21 produce a satisfactory core support for the bristles.

The handle 10 is preferably a knurled cylindrical head although other types may be used. A most satisfactory form of spring 12 is produced when spring stock of rectangular cross section as shown in Fig. 3 is bent into a helix. This type of coil seems to provide maximum flexibility in conjunction with great torque transmitting capacity even when the spring is bent into an acute angle. However, spring wire which is circular in cross section or other flexible material may be employed. The spring engaging

ends of the shank 11 and the chuck element 13 are preferably of reduced diameter so as to be seated in several of the convolutions of the coil; see Figs. 2 and 3. Welding or brazing at these zones may be employed to produce a secure bond.

The threaded collar 14 is arranged to rotate freely and reciprocate axially a limited distance on chuck element 13. This chuck element is provided with an enlarged head 22, the rear face 23 of which is conditioned to engage the annular shoulder 24 at the rear of the collar 14; see

Fig. 3. This prevents the collar from dropping off the end of chuck and becoming lost. The periphery of the collar may be knurled to facilitate its rotation by the fingers.

Chuck engaging element 15 is internally threaded at its forward end 17 in order that a new cleaning attachment may be inserted when the old brush member 19 becomes worn.

Fig. 5 illustrates a swab tip 25 conditioned to be interlocked with notched chuck element 13 and having an elongated ring 26 at its free end. Ring 26 is adapted to receive a fabric swab (not shown) for use in the final cleaning operation on the barrel chamber.

The use of the implement is as follows: With the tool assembled as in Fig. 1, the flexible portion is bent into an abrupt angle as shown in Fig. 4 and the brush attachment 19 is inserted a suitable distance in the barrel chamber. Combined axial pressure in the direction of the muzzle of the gun and rotation imparted with the fingers on the knurled handle 10 progressively advances the brush into the bore. The brush immediately assumes a position coaxial with the bore and proceeds to clean the wall of the barrel chamber uniformly. The spring 12 permits the application of ample torque for rotation in one direction or for oscillatory movement. Furthermore the creation of a sharp bend avoids interference with such gun components as the follower 27 and miscellaneous elements and surfaces on the receiver 28 as represented in Fig. 4. This results in a quick effective uniform cleaning of the barrel chamber.

The tool is removed from the barrel and the

brush attachment 19 is replaced by the swab tip 25 in the following manner. Collar 14 is rotated so as to remove chuck engaging element 15 from threaded engagement therewith. The notched portion of the swab tip 25 is placed in interlocking relation with the notched portion of chuck element 13 and then the threaded collar 14 is tightened on the threaded notched portion of the swab tip. This couples the members together and a suitable swab may be inserted through the ring 26 and wrapped about the tip. The barrel chamber is then polished in the manner previously described in connection with the brushing operation.

I claim:

1. A barrel cleaning device comprising a three part cleaning member holder of inflexible sections including a handle member and shank thereon, a threaded shouldered end member for attachment to a cleaning member, an intermediate member provided with a shouldered head for cooperating with the shoulder on the end member, a threaded sleeve coupling the end member and intermediate member, and a spiral spring connecting the handle shank member with the intermediate member and adapted to transmit torque when the device is rotated on a non-rectilinear axis.

2. The invention of claim 1 characterized in that the sleeve is provided with a flange for engagement with the head on the intermediate member to prevent displacement of said sleeve from said intermediate member.

CARL W. GILLIGAN.
